FOCUSING DEVICE FOR HEADLIGHTS

1,426,858.

Specification of Letters Patent. Patented Aug. 22, 1922.

Application filed January 10, 1921. Serial No. 436,097.

To all whom it may concern:

Be it known that I, CHARLES E. GODLEY, a citizen of the United States, and residing at Detroit, in the county of Wayne and 5 State of Michigan, have invented a new and Improved Focusing Device for Headlights, of which the following is a specification.

This invention relates to means for movably supporting the active light giving portion 10 of an incandescent light bulb along or transversely to the focal axes of lamps of the headlight type, and its object is to provide simple and effective mechanism to accomplish this object.

15 This invention consists, in combination with a cup-shaped lamp body having a central aperture, of a connector sleeve extending into this aperture and so much smaller in diameter than the aperture that it may be shifted laterally therein, of a pair of 20 plates gripping between them the metal of the body around the aperture and in which plates the connector is slidably, and a screw mounted in said plates for sliding the sleeve 25 longitudinally.

It further consists in a lamp as above described, of a reflector therein having a central aperture for the connector sleeve of substantially the same diameter as that of the body, the body around its aperture being flat.

30 It also consists of the details of construction illustrated in the accompanying drawing and particularly pointed out in the 35 claims.

In the accompanying drawing, Fig. 1 is a central longitudinal section of a lamp embodying the present invention. Fig. 2 is a section on the line 2-2 of Fig. 1. Fig. 3 40 is a section similar to Fig. 1 showing a modified form of focusing device.

Similar reference characters refer to like parts throughout the several views.

The focusing device herein set forth is of 45 the type shown in my prior application Serial Number 430,958, filed December 15, 1920.

50 The cup-shaped body 1 has a flat preferably central end portion 2 provided with an aperture 4 and the reflector 3 within the body has an aperture 5. The connector sleeve 6 receives the usual connector plug 7 at one end, the plug carrying the conductor wire 8. The front end of the connector 55 receives the base 9 of the light bulb 10 whose filament has an active light giving portion

11. The sleeve 6 may be of any desired construction, the patent to Knauff, Number 1,059,617, dated April 22, 1913, showing a connector well adapted for this purpose. 60

The sleeve 6 has a circumferential groove 12 which received the clip 13 provided with a rearwardly extending finger 14 which fits in a notch in the collar 19. Plates 15 and 16 fit against opposite sides of the part 2 65 of the body 1 and a screw 17 extends through these plates and is screw threaded into a small arm 18 on the sleeve 6. A spring 20 between the collar 19 and plate 15 causes this collar to press the bracket 70 18 forward, causes the screw 17 to pull the plate 16 against the part 2 of the body, and presses the plate 15 back against the body. The plates 15 and 16 therefore so firmly grip the metal of the body around the aperture 75 4 that the connector sleeve 6 and the light bulb are firmly held in the desired position.

The distance from the part 11 of the filament of the bulb to the base 9 varies so that longitudinal adjustment is necessary to position each type of bulb. The portion 11 of the filament is not always central with the base 9 and it is often impossible to properly focus lamps provided with the usual focusing devices found in the headlights of automobiles because of the active part of the filament being so far to one side of the focal axis of the reflector. By the use of the present device, however, the active part of the filament may be moved laterally into the 80 focus of the reflector in order to produce perfect focusing or it may be moved away from this focus when a diffused light is desired. 85

I provide a small pin 21 in the screw 17 95 to prevent the parts being disengaged unintentionally. When the parts are to be removed, the reflector and light bulb are removed, this pin 21 is taken out and the screw 17 turned until the bracket 18 is freed 100 therefrom. The sleeve may then be drawn forward out of the plates 15 and 16.

In Fig. 3 the central part 2^a of the body has an aperture 4^a to permit the sleeve 6 to move around in any desired direction, the 105 center of curvature of this part 2^a and of the plates 15^a and 16^a being the middle of the aperture 5^a in the reflector 3. The other parts of the focusing device are the same as those above described and have the same 110 functions.

The plates 16 and 16^a are formed with

- circumferential flanges 22 and 22^a which afford good grasping surfaces when the connector sleeve is to be shifted laterally in the apertures 4 and 4^a. The aperture 5^a need be but little larger than the sleeve 6 to permit this lateral movement of the outer end of the connector sleeve as the movement of the outer end of the sleeve is concentric with the middle of this aperture 5^a.
- 10 The details and proportions of the various parts of this focusing device may all be changed by those skilled in the art without departing from the spirit of my invention as set forth in the following claims.
- 15 I claim:
1. In a headlight, the combination of a cup-shaped lamp body having a central opening, a pair of plates slidably fitting said body around the aperture, a connector sleeve 20 slidably mounted in said plates and movable laterally within said aperture, a screw mounted in said plates to adjust the sleeve longitudinally, a spring mounted on the sleeve to cause the plates to grip the metal of the body between them, said sleeve being formed with a circumferential groove, 25 a clip in said groove, and a collar on said sleeve and engaging the clip to serve as an abutment for said spring.
  2. In a headlight, the combination of a lamp body having an aperture, a pair of plates slidably fitting the lamp body around said aperture, a connector sleeve mounted in said plates and movable laterally within 30 said aperture, a bracket attached to the sleeve, means supported by said plates and
  3. In a headlight, the combination of a cup-shaped lamp body having a flattened rear end and a central aperture therein, a pair of flat plates slidably fitting said flattened portion around the aperture, a connector sleeve slidably mounted in said plates and movable laterally within said aperture, a screw mounted in said plates to adjust the sleeve longitudinally, a spring mounted on the sleeve to cause the plates to grip the metal of the body between them and means mounted on the sleeve to serve as an abutment for the spring.
  4. In a headlight, the combination of a cup-shaped lamp body having a flattened rear end and a central aperture therein, a pair of flat plates slidably fitting said flattened portion around the aperture, a connector sleeve slidably mounted in said plates and movable laterally within said aperture, 55 a screw mounted in said plates to adjust the sleeve longitudinally, a spring mounted on the sleeve to cause the plates to grip the metal of the body between them, said sleeve being formed with a circumferential groove, a clip in said groove, and a collar on said sleeve and engaging the clip to serve as an abutment for said spring.

CHARLES E. GODLEY.
